UNITED STATES PATENT OFFICE

145,103

DESIGN FOR A BOOK STAND

George Powers, Alameda, Calif.

Application June 29, 1945, Serial No. 120,398

Term of patent 7 years

(Cl. D33—2)

To all whom it may concern:

Be it known that I, George Powers, a citizen of the United States, and a resident of Alameda, in the county of Alameda and State of California, have invented a new, original, and ornamental Design for a Book Stand, of which the following is a specification, reference being had to the accompanying drawings, forming part thereof, wherein

I claim:

The ornamental design for a book stand, substantially as shown.

GEORGE POWERS.
